UNITED STATES PATENT OFFICE.

THEODORE W. WASHBURN, OF BALDWINVILLE, MASSACHUSETTS, ASSIGNOR
TO GILMAN WAITE, OF BALDWINVILLE, MASSACHUSETTS.

LOCKING DEVICE FOR CHAIRS OR THE LIKE.

SPECIFICATION forming part of Letters Patent No. 727,866, dated May 12, 1903.

Application filed January 9, 1902. Serial No. 88,993. (No model.)

To all whom it may concern:

Be it known that I, THEODORE W. WASHBURN, of Baldwinville, in the county of Worcester and State of Massachusetts, have 5 invented an Improved Locking Device for Chairs or the Like, of which the following is a specification.

My invention relates particularly to locking devices for children's chairs which have 10 a table adapted to rest upon the arms of the chair when in use and adapted to be swung out of the way when not in use; and it consists in adjustable means for locking the table to the chair.

15 In the drawings, Figure 1 is a side view of a chair embodying my invention. Fig. 2 is a front view, partly in section. Fig. 3 is an elevation; and Fig. 4 is a section on line 4-4, showing my new adjustable guide-plate.

20 A is a chair having arms *a*, which are grooved at *a'*.

B is a table attached to rods *b*, pivoted at *b'*.

D is a spring-wire attached to the table by staples *d*.

25 *F* is a guide-plate slotted at *f* for spring *D*, and its upper portion *f'* fits the rod *b* and has a slot *f''*, which enables the guide to be attached to the rod in the desired position by a screw *f'''*, as shown. The slot *f* receives the 30 end of the spring *D* and guides the spring into proper engagement with groove *a'* in arm *a*. When the table is brought to place, the end of the spring *D* snaps over the end of arm *a* into engagement with the groove *a'*, the guide-plate *F* insuring such engagement.

The relation between the arms *a* of the chair and the spring *D*, carried by the table *B* when the rods *b* are connected by their pivots *b'* to the chair *A*, must be such that the ends of 40 the spring *D* will press against the bottoms

of the grooves *a'*, and this is a matter of comparatively nice adjustment; but that nice adjustment is readily attained by the proper adjustment of my guide-plate *F*, which can be brought into proper position to so hold the 45 end of spring *D* that it will snap on the end of arm *a* into groove *a'* as the table *B* is swung into place. Moreover, the curve of rods *b* is apt to vary slightly not only in different tables of the same lot, but also any rod is liable 50 to become slightly less curved from lapse of time or from use, and the guide-plate *F* then requires readjustment.

Heretofore the only guide for the end of spring *B* has been a staple driven into the 55 under side of rod *b*, and I am the first, so far as I have any reason to believe, to use a guide-slot in a plate adjustably secured to rod *b*.

What I claim as my invention is—

In combination a chair; its arms grooved 60 at their outer ends; a table swinging on rods pivoted to the chair and resting on the arms of the chair; a spring-rod carried by the table and engaging the grooves in the outer ends of the arms of the chair; a guide-plate whose 65 upper portion is shaped to fit the pivoted rod of the table and slotted for adjustment parallel with the rod, and whose lower portion has a slot parallel with the adjusting-slot to receive the end of the spring-rod, and hold 70 that rod in proper relation with the groove in the outer end of the arm of the chair; and a screw through the upper slot of the guide-plate for holding the guide-plate adjustably to the pivoted rod of the table.

THEODORE W. WASHBURN.
